UNITED STATES PATENT OFFICE.

WALTER L. C. NILES, OF SAUGUS, MASSACHUSETTS, ASSIGNOR TO EXCEL SHOE FORM COMPANY, OF LYNN, MASSACHUSETTS, A CORPORATION OF MASSACHUSETTS.

SHOE FORM.

Application filed February 19, 1927. Serial No. 169,616.

This invention relates to forms employed by salesmen and others to display shoes and has for its general object to provide a form which will hold a shoe expanded and in a natural and attractive shape but which will not obstruct the interior of the shoe to such an extent as to conceal the lining, whereby the interior as well as the exterior of the shoe may be readily inspected.

10 The nature of the invention will best be understood from the following description of certain forms or embodiments thereof illustrated in the accompanying drawings. It will be understood, however, that the 15 particular constructions described and shown have been chosen for purposes of exemplification merely, and that the invention, as defined by the claims hereunto appended, may be otherwise embodied without 20 departure from the spirit and scope thereof.

In said drawings.

Fig. 1 is a longitudinal section of a shoe, showing the form in position therein.

Fig. 2 is a bottom plan view of the form 15 removed.

Fig. 3 is a similar view of a modified construction.

Fig. 4 is a detail view, on a reduced scale, of the spreader member of the form.

30 As herein shown, the form comprises a toe member 10, shaped to enter and substantially fit the interior of the toe portion of a shoe, and a resilient skeleton spreader member 11 connected to the toe member and extending therefrom to the rear end of the shoe. The toe member 10, which is preferably of hollow construction with an open bottom, may be composed of any suitable material, such as fibre, and terminates at the 35 rear end of the toe portion of the shoe, the sides of said member adjacent their ends being braced or spaced by a suitable cross member or strut 12. The spreader member 11 may comprise a loop of relatively heavy 40 spring wire of a suitable size and shape to extend about and substantially fit the sides, quarters and counter of the shoe. In the preferred construction shown, the ends of the loop 11 are connected to each other and 45 to the toe member 11 at a point well in front of the rise of the instep. As shown in Fig. 4, the ends of the loop 11 are formed with eyes 13 to receive a stud 14 which extends through the top wall of the toe member 10, 50 is provided at the outer side of the latter

with a head 15, and has a threaded inner end to receive a nut 16, said stud and nut constituting a clamp for connecting the forward ends of the spreader member or loop to the under surface of the top wall of the toe member. In order to adapt the form to shoes of different sizes, this connection is preferably made adjustable, as by forming the toe member with a series of holes 17 to receive the stud 14, as shown in Fig. 2. If preferred, the holes 17 may be replaced by a slot 18, as shown in Fig. 3, in which the stud 14 is adjustably held by the clamping action of the nut 16.

When the form above described is in position in a shoe, as shown in Fig. 1, the latter will be held distended in the manner desired for display purposes, but, by reason of the skeleton nature of the form, and particularly of the spreader member 11 thereof, the interior of the shoe will not be obstructed or concealed to any material extent. Due to the attachment of the spreader member to the toe member at a point in front of the rise of the instep, the forward end of the toe member is forced downwardly into the forward end of the toe portion of the shoe, thereby preventing upward curling of the shoe and holding the shoe bottom to the true tread. Moreover, since the loop 11 is both laterally and longitudinally resilient, the effect of the longitudinal pressure thereof against the rear end of the shoe will be not only to force the toe portion into place, but also to expand the spreader laterally, as indicated in broken lines in Fig. 2, thereby spreading the quarters of the shoe to the same extent as a complete form but without the obstruction interposed by the latter to free inspection of the interior of the shoe.

Having thus described my invention, I claim:

1. A shoe form including a toe member adapted to fit in the toe portion of a shoe and a resilient spreader member connected to the toe member and adapted to fit in that portion of the shoe lying back of the toe portion thereof with tensional bearing against the interior of the sides and end of the shoe.

2. A shoe form including a toe member adapted to fit in the toe portion of the shoe and a resilient spreader member adapted to fit in that portion of the shoe lying back of the toe portion thereof and when in

place having tensional bearing in part against the end of the shoe and in other parts against the interior of its opposite sides with extension along said sides, the 5 spreader member being connected to the toe member, and means for making such connection.

3. A shoe form including a toe member adapted to fit within the toe portion of 10 a shoe and a resilient spreader member adapted to fit in that portion of the shoe lying back of its toe portion with tensional bearing against the end and opposite sides of the shoe, those portions of the resilient 15 member bearing against the opposite sides of the shoe extending along said sides and connected to the toe member in position where the pressure exerted by the resilient member when in place will tend to force 20 down the forward end of the toe member into the forward end of the toe portion of the shoe, and means for making such connection.

4. A shoe form including a toe member adapted to fit within the toe portion of a 25 shoe and a resilient loop connected to the toe member adapted to fit within that portion of the shoe lying back of its toe portion and when in place extending from the toe member about the quarters and counter 30 of the shoe with tensional bearing against said quarters and counter.

5. A shoe form including a toe member

adapted to fit within the toe portion of a shoe and a resilient loop connected to the toe member adapted to fit within that portion of the shoe lying back of its toe portion and when in place extending from the toe member about the quarters and counter of the shoe with tensional bearing against said quarters and counter, those portions of the 40 loop extending about the quarters of the shoe being connected to the toe member in position where the pressure exerted by the resilient loop when in place will tend to force down the forward end of the toe member 45 into the forward end of the toe portion of the shoe, and means for making such connection.

6. A shoe form including a toe member and a resilient loop extending from said toe 50 member about the quarters and counter of the shoe, and an adjustable clamp connecting the ends of said loop with each other and with said toe member.

7. A shoe form including a toe member 55 and a resilient loop extending from said toe member about the quarters and counter of the shoe, and an adjustable clamp connecting the ends of said loop with each other and with said toe member at a point in front 60 of the rise of the instep.

In testimony whereof I affix my signature.

WALTER L. C. NILES.
